US00D860990S

(12) **United States Design Patent** (10) **Patent No.:** **US D860,990 S**
(45) **Date of Patent:** **** Sep. 24, 2019**

(54) **MOBILE TERMINAL**

(71) Applicant: **ZTE CORPORATION**, Guangdong (CN)

(72) Inventors: **Ye Tian**, Guangdong (CN); **Tao Yan**, Guangdong (CN)

(73) Assignee: **ZTE CORPORATION** (CN)

(**) Term: **15 Years**

(21) Appl. No.: **35/504,722**

(22) Filed: **Jan. 30, 2018**

(80) **Hague Agreement Data**

Int. Filing Date: **Jan. 30, 2018**

Int. Reg. No.: **DM/100372**

Int. Reg. Date: **Jan. 30, 2018**

Int. Reg. Pub. Date: **Apr. 6, 2018**

(51) **LOC (12) Cl.** **14-02**

(52) **U.S. Cl.**

USPC ..... **D14/345**; D14/138 AB

(58) **Field of Classification Search**

(57) **CLAIM**

The ornamental design for a mobile terminal, as shown and described.

DESCRIPTION

1. Mobile terminal

1.1 : Perspective

1.2 : Perspective

1.3 : Front

1.4 : Back

1.5 : Left

1.6 : Right

1.7 : Top

1.8 : Bottom

1.9 : Perspective

1.10 : Perspective

1.11 : Front

1.12 : Back

1.13 : Left

1.14 : Right

1.15 : Top

1.16 : Bottom

Figures 1.1-1.8 show a mobile terminal being in a closed position and figures 1.9-1.16 show the mobile terminal being in an open position.

1 Claim, 16 Drawing Sheets
